UNITED STATES PATENT OFFICE.

CHARLES W. HICKS, OF CLEARWATER, FLORIDA.

SUBSOIL-PLOW.

1,079,553.

Specification of Letters Patent. Patented Nov. 25, 1913.

Application filed November 4, 1912. Serial No. 729,194.

To all whom it may concern:

Be it known that I, CHARLES W. HICKS, a citizen of the United States, residing at Clearwater, in the county of Pinellas and State of Florida, have invented new and useful Improvements in Subsoil-Plows, of which the following is a specification.

This invention relates to attachments for subsoil plows, and it comprehends, briefly, certain hereinafter described improvements in the type of attachments shown in my prior application, Serial Number 707,576, filed July 3, 1912. The improvements in question reside primarily in the construction 15 of the guide brackets associated with the shoe-carrying bar, the mounting of said brackets upon their supporting bar, and the devices employed to connect the same with the plow beam, their object being 20 to avoid and correct any deviation of the shoe from its proper working position, and, also, to permit the employment of the ordinary furrow-turning share or with a middle breaker.

25 An embodiment of the invention is illustrated in the accompanying drawing, whereof:—

Figure 1 is a side elevation of a plow equipped with the improved attachment; 30 Fig. 2 is an enlarged plan view of the attachment, the plow beam being shown in section, and the shoe-carrying bar omitted; Fig. 3 is a perspective view of the attachment, with the upper guide bracket removed from 35 its supporting bar, the shoe and a portion of its bar being shown.

The plow represented in said drawing is of the conventional "goose-neck" style, and comprises, generally, the curved metal beam 40 1, handles 2, and share 3. These parts are of the ordinary construction, and the term "share," as applied to the last-mentioned element, is employed in its broadest sense, *i. e.*, as indicating any one of the commonly-45 used ground treating devices, without reference to the specific structural characteristics thereof; it is here shown as a furrow turner.

The sub-soil attachment is located between the handles, and to the rear of the beam, as 50 shown, its chief element being the vertical bar 4 which is formed along one edge with a series of notches 5 and carries at its lower end the shoe 6. To guide this bar in its movements, upper and lower brackets 7 and 55 8 having slots 9 and 10 are employed, said

brackets being connected to and carried by a suitable supporting bar 11 which, in turn, is connected to the beam.

In the present embodiment of the invention, the aforesaid supporting bar 11 has the 30 shape of a right angle, its horizontal upper arm being provided with a terminal clamp 12 that is similar, in the main, to the corresponding element shown in my previously-identified application, to which reference 35 may be had for a complete description; it is sufficient to state, therefore, that the jaws of the clamp straddle the grooved plow beam and grip the same at opposite sides, suitable clamping bolts 13 being employed to hold 70 the jaws in place. The arms of the supporting bar are connected by a diagonally-arranged brace rod 14 which is detachably fastened at its ends to lugs 15 formed on the arm ends; as depicted in Fig. 3, the rod 75 having, by preference, an arcuate shape to permit it to pass under or over any of the usual connecting braces carried by the plow proper, which braces might otherwise interfere with its attachment to the supporting 80 bar.

As more particularly regards the guide brackets above referred to, it may be stated that the lower bracket 8, for reasons herein-after explained, is of duplex formation; 85 that is to say, it comprises a pair of counterpart members which are located upon opposite sides of the vertical arm of the supporting bar 11 at the lower end thereof and occupy a common horizontal plane. The upper 90 bracket 7 is removably mounted upon the rear end of the horizontal arm of bar 11, and is of substantially angle section, its horizontal, upper plate-like member or wing, wherein the slot 9 is formed, being extended 95 a slight distance beyond the vertical wing to produce a supporting lip or flange 16 that is adapted to rest upon the upper edge of the horizontal arm of said bar 11. The vertical arm of this bracket may be placed 100 against either side face of the horizontal arm of bar 11, according as it is to co-operate with one or the other of the members of bracket 8, and it is formed adjacent each end with an opening 17 through either of which a fastening bolt 18 may be passed to attach the bracket to its supporting arm, the stem of the bolt passing through a short longitudinal slot 19 in said arm. This construction, as will be understood, affords a 110

slight sliding adjustment of the upper bracket, and, also, permits the same to be reversed, to arrange its slot 9 above either slot 10 in the lower bracket. In consequence, it is possible to dispose the shoe-carrying bar 4 against either side of the supporting bar 11 according as it is to be used with either a furrow-turner or a middle breaker. In the former instance, the parts 10 are arranged in the manner shown, with the bar 4 disposed upon the right-hand side of bar 11, but in the latter instance, (which it is deemed unnecessary to illustrate), bar 4 is arranged upon the left-hand side of bar 11 so as to dispose the axis of the shoe in line with the center of the middle breaker. By adjusting the slidable upper bracket, the shoe 6 may be caused to enter the ground in the proper position, thus rendering it possible to initially position the shoe correctly, or to re-position the shoe if, for any reason, it has assumed an incorrect position during either the connection of the attachment to the plow, or when the latter is in use.

25 In addition to the clamp 12, the attachment is preferably fastened to the plow through the agency of a rod 20. This rod, which is of considerable length, is provided at its front end with an eye 21 that may be engaged with any one of the usual plow bolts; for example, one of the bolts 22 used to fasten the share to the beam. The rear half of said rod is threaded, and this portion is passed through any one of a vertical series 30 of perforations 23 formed in a vertical flange 24 that projects laterally from the front edge of the depending arm of bar 11, the flange being preferably integral with said arm and the adjacent member of bracket 8. As a result of this construction, the connecting rod 20 may be fastened in different positions and at different angles, to insure the retention of the supporting bar in proper position relative to the plow proper, 35 suitable fastening nuts 25 being employed to secure the rod as adjusted, these nuts engaging against the opposite faces of flange 24.

40 To retain the shoe carrying bar 4 in adjusted position, a suitable key 28 or the like may be employed.

I claim:—

1. In a plow, the combination, with a supporting bar adapted for connection to the plow beam; of a pair of superposed guide brackets carried by said bar; and an endwise movable element slidably engaged with said brackets, one of the brackets being movable relatively to the other to vary the position of said element.

2. In a plow, the combination, with a supporting bar adapted for connection to the plow beam; of a pair of counter-part guides carried by said bar adjacent the lower end 65 thereof; a reversible guide removably con-

nected to the upper portion of said bar for coöperation with either of the first-named guides; and an endwise movable element slidably engaged with the reversible guide and with the adjacent first-named guide.

3. In a plow, the combination, with an angular supporting bar adapted for connection to the plow beam; of a pair of superposed guide brackets secured, one to the horizontal arm and the other to the vertical arm of said bar; and an endwise movable element slidably engaged with said brackets, one of the brackets being movable relatively to the other, to vary the position of said element.

4. In a plow, the combination with a supporting bar adapted for connection to the plow beam; of a pair of counter-part guides carried by said bar adjacent the lower end thereof; a slidable and reversible guide removably connected to the upper portion of said bar for coöperation with either of the first-named guides; and an endwise movable element slidably engaged with the second-named guide and with the adjacent first-named guide.

5. In a plow, the combination with an angular supporting bar adapted for connection to the plow beam and embodying an upper horizontal arm and a lower vertical arm; of a slidable guide bracket secured to the horizontal arm; a guide bracket fixed to the vertical arm beneath the first-named bracket; and an endwise movable element slidably engaged with said brackets.

6. In a plow, the combination, with a supporting bar adapted for connection to the plow beam, and guide means carried by said bar; of an endwise movable element slidably engaged with said guide means; a lateral flange provided upon said bar and having a perforation formed therein; a tie-rod connected at its front end with said beam and having its rear portion extending through the perforation in said flange; and fastening means carried by said rod and engaged with said flange.

7. In a plow, the combination with a supporting bar adapted for connection to the plow beam and provided with guide means and with a vertical series of perforations; of an endwise movable element slidably engaged with said guide means; and a tie-rod having its front end pivotally connected to one of the plow bolts and its rear portion interchangeably engaged in said perforations.

8. In a plow, the combination, with an angular supporting bar adapted for connection to the plow-beam and embodying an upper horizontal arm and a lower vertical arm; of a pair of counter-part guides fixed to the vertical arm; a reversible guide removably connected to the horizontal arm; and an endwise movable element slidably

engaged with the reversible guide and with the adjacent first-named guide.

9. In a plow, the combination, with an angular supporting bar adapted for connection to the plow-beam and embodying an upper horizontal arm and a lower vertical arm; of a pair of slotted, counter-part guides fixed to the vertical arm; a slotted, reversible guide slidably and removably connected to the horizontal arm; and an endwise movable element slidably engaged in the slot in said reversible guide and the slot in the adjacent first-named guide.

10. In a plow, the combination, with an angular supporting bar adapted for connection to the plow-beam and embodying an upper horizontal arm and a lower vertical arm; of a pair of counter-part guides fixed to the vertical arm; a reversible guide of angle section mounted on the horizontal arm and embodying a horizontal wing provided with a supporting flange adapted to rest upon the upper edge of said horizontal arm, and a vertical wing adapted for attachment to either side face of that arm; and an endwise movable element slidably engaged with the horizontal wing of said reversible guide and with the adjacent first-named guide.

11. In a plow, the combination, with an angular supporting bar adapted for connection to the plow beam and embodying an

upper horizontal arm and a lower vertical arm; of a slideable guide bracket of angle section embodying a horizontal wing provided with a lip adapted to rest upon the upper edge of the horizontal arm, and a vertical wing adapted for adjustable attachment to one of the side faces of that arm; a guide bracket fixed to the vertical arm of said bar beneath the first-named bracket; and an endwise movable element slidably engaged with the horizontal wing of said first-named bracket and with the second-named bracket.

12. In a plow, the combination, with a supporting bar adapted for connection to the plow beam; of a pair of counter-part guides connected to opposite sides of said beam; a reversible guide adapted for connection to either side of said beam; and an endwise movable element slidably engaged with the reversible guide and the first-named guide on the same side of the beam as said reversible guide.

In testimony whereof I have hereunto set my hand in presence of two subscribing witnesses.

CHARLES W. HICKS.
